Fig. 1.

Fig. 3.

Fig. 2.

Fig. 4.

FIG. 1 is a front elevational view of an automobile window louver showing my new design, which is adapted to be mounted on the left side window of an automobile, it being understood that the broken lines are for illustrative purposes only;

FIG. 2 is an enlarged front elevational view thereof;

FIG. 3 is an enlarged top plan view thereof;

FIG. 4 is an enlarged bottom plan view thereof;

FIG. 5 is an enlarged rear elevational view thereof;

FIG. 6 is an enlarged right end elevational view thereof;

FIG. 7 is an enlarged left end elevational view thereof;

FIG. 8 is an enlarged sectional view thereof taken along the line 8-8 of FIG. 2; and

FIG. 9 is a front elevational view of an automobile window louver showing a second embodiment of my new design which is adapted to be mounted on the right side window of an automobile, it being understood that the top, bottom, rear and ends of said embodiment are mirror images of the top, bottom, rear and ends of the automobile window louver shown in FIGS. 3 through 7, respectively.

I claim:

The ornamental design for an automobile window louver, substantially as shown and described.
